ROTARY ENGINE

This application is a continuation of Ser. No. 773,562, filed Nov. 5, 1968, and now abandoned.

This invention relates to rotary engines of the type described in U.S. Pat. No. 3,354,871 and constitutes an improvement thereon.

The invention will be described in detail in the preferred form as an internal combustion engine; however, the principles and basic elements of the invention are also applicable for use in other forms of propulsion devices, such as steam engines or the like.

As in the rotary engine described in U.S. Pat. No. 3,354,871, the engine of this invention comprises a housing having inlet and exhaust ports in communication with an annular piston chamber, a central rotary means, planetary piston means with at least one piston revolvable around the periphery of the central rotary means within the annular piston chamber, a rotary cutoff means adapted to cooperate with the piston and central rotary means to provide compression and expansion zones in the annular piston chamber, power output means rotated by revolution of the planetary piston means, and means for rotating the central rotary means and the rotary cutoff means in response to revolution of the planetary piston means such that the piston successively closes off combustion chambers from the compression and expansion zones. The central rotary means comprises a rotatably mounted combustion rotor, which, together with the housing, defines the annular piston chamber immediately surrounding the combustion rotor periphery. The plurality of combustion chambers are contained in the combustion rotor in communication with the annular piston chamber. The rotary cutoff means comprises a cutoff rotor rotatably mounted in the housing to intersect the annular piston chamber and sweep, or wipe, the combustion rotor periphery such that the annular piston chamber is divided into compression and expansion zones. The cutoff rotor contains at least one piston recess for receiving therein a piston of the planetary piston means to permit passage of the piston as it revolves around the combustion rotor. The leading and trailing ends of the piston and piston recess are contoured to be swept, or wiped, by leading and trailing edges of the other as the piston travels into and out of mesh with the piston recess so that the division of the annular piston chamber into compression and expansion zones is maintained as the piston travels past the rotary cutoff means. Two rotary cutoff means are preferably provided at diametrically opposite locations across the combustion rotor and at least two, and preferably four, pistons are also provided so that balanced compressions, combustions, and expansions can occur.

The specific embodiment of the engine of U.S. Pat. No. 3,354,871 is intended for air cooling, rotation of its central rotor is effected through planetary gearing, and power output is effected through a strut interconnecting two axially aligned shafts. The combination of these features poses shaft bearings, sealing, cooling, center shaft stability, fuel injection and overall size problems.

It is accordingly an object of this invention to provide a rotary internal combustion engine of the Skrob type incorporating internal cooling, a through power output shaft and improved shaft bearing rotary seal characteristics, all to the point of providing an improved Skrob engine. Another object of this invention is to provide an improved combustion rotor and piston design and an improved cutoff rotor design to further enhance the operating characteristics of such an engine.

These and other objects and advantages will become apparent from the following description in conjunction with the accompanying drawings, of which:

FIG. 1 is a cross-sectional detail of an exemplary embodiment of this invention;

FIG. 2 is a cross section view taken along the line 2-2 of FIG. 1;

FIG. 3 is an elevational detail view illustrating a piston of the FIG. 1 embodiment positioned in FIG. 2; and

FIGS. 4-11 are schematic views sequentially illustrating the relationship of the major revolving components of the FIG. 1 embodiment.

As shown in the drawings, the depicted embodiment of this invention includes the major revolving elements necessary to the Skrob-type engine incorporated within a housing 10; namely, a central rotary means 12, planetary piston means 14, two rotary cutoff means 16 and 18, power output means 20, and means 22 for rotating the central rotary means and rotary cutoff means in response to revolution of the planetary piston means. The housing 10 comprises four peripherally flanged members 1, 2, 3 and 4 that are bolted together about their peripheries to provide a bearing and air reservoir section 10a, a combustion section 10b, a shaft support section 10c and a gear box section 10d. The combustion section contains an annular piston chamber 52 with two sets of inlet and outlet ports 51-53 provided at diametrically opposite locations at approximately 90° spacing relative to the rotary cutoff means.

The central rotary means 12 comprises a combustion rotor 24 axially secured to a hollow shaft 26. The combustion rotor comprises a circular disc having an enlarged peripheral annular section presenting a flat outer peripheral edge surface and parallel, flat side surfaces normal to the edge surface. A plurality (six) of relatively deep secondary combustion chambers 28 of generally cylindrical configuration are contained within the combustion rotor enlarged peripheral section and spaced uniformly therearound. The secondary combustion chambers open outwardly through the combustion rotor outer peripheral edge surface. A plurality (six) of relatively shallow primary combustion chambers 29 of generally semicircular configuration are contained within one of the normal flat side surfaces (which surface is designated as the inner side for reference purposes) and are spaced therearound in superimposition to the secondary combustion chambers. The primary combustion chambers open outwardly through the combustion rotor outer peripheral edge surface in staggered relation to the respective secondary combustion chamber such that the trailing edges of the primary combustion chamber openings lags the trailing edges of the respective secondary combustion chambers openings.

The housing 10 is provided at diametrically opposite locations with two fuel-injecting means 30 and two fuel-igniting spark plug means 32 (unless the engine operates on the diesel cycle in which case a compressed mixture of fuel and air would be self-igniting) and with fuel inlet ports opening to the inner side surface of the combustion rotor enlarged peripheral section for communication with the primary combustion chambers. The housing wall adjacent to the combustion rotor inner side closely parallels the rotor inner side and the two are provided with a mated annular step and channel pressure seal 34 located radially inward of the rotor-enlarged peripheral section.

The planetary piston means 14 comprises four piston sections 36, 38, 40 and 42 spaced 90° apart and interconnected to an integral flywheel disc section 44. The flywheel disc is axially secured to a through drive shaft 48 that is concentrically enclosed by combustion rotor shaft 26. The inner side of the flywheel disc and the outer side of the combustion rotor closely parallel one another and are provided with a mated annular step and channel pressure seal 50 located at the outer side surface of the combustion rotor enlarged peripheral section. The housing wall adjacent to the flywheel disc closely parallels the disc outer side and the two are provided with a mated annular step and channel pressure seal 55. The piston sections are provided with semicircular arcuate inner and outer side surfaces, the inner side being adapted to sweep the outer side edge of the combustion rotor to alternately seal off and expose the openings of the primary and secondary combustion chambers, and the outer side being adapted to sweep a semicircular wall of the housing 10, which housing wall together with the combustion rotor outer edge defines an annular piston chamber 52.

The piston means is positioned adjacent the combustion rotor side opposite to the side facing the housing gearbox section. This enables the drive shaft 48 to be provided as a center through shaft. This also enables the location of the fuel combustion means in an easily accessible location without disrupting the continuity of the engine housing.

The rotary cutoff means 16 and 18 each comprise a cutoff rotor 54 axially secured to a shaft 56. The cutoff rotor peripheral edge is provided with two diametrically opposed piston recess 58—60 adapted to mesh with the piston sections. The leading and trailing end surfaces of the piston sections are concave such that the piston sections will cooperatively mesh with the piston recesses to maintain pressure seals between the compression and expansion zones of the piston chamber during passage of the piston sections through the piston recesses. The cutoff rotor contains a toroidal accumulator chamber 62 communicating with each piston recess through normally closed pressure-opening relief valves 64—66 which open to the trailing ends of the respective piston recesses. The housing sections encasing the cutoff rotors are each provided with an annular passage 68 open to the cutoff rotor-housing chamber and communicating with the toroidal accumulator through an open port 70 extending through one sidewall of the cutoff rotor. Each passage 68 is bracketed by mated annular step and channel pressure seals 72—74 provided in the adjacent surfaces of the housing and cutoff rotor side. The opposite adjacent surfaces of the housing and cutoff rotor side are also provided with a mated annular step and channel pressure seal 76.

In the housing gearbox section, the output drive shaft is provided with a drive gear 80 meshed with a driven gear 82 which is secured to the cutoff rotor shaft, and the cutoff rotor shaft is provided with a drive gear 84 meshed with a driven gear 86 which is secured to the combustion rotor shaft. These gears are sized to provide a cutoff rotor angular speed twice that of the piston means, and a combustion rotor angular speed two-thirds that of the piston means. Shafts 48 and 56 are mounted in the housing by suitable oil-lubricated bearings 90, 92, 94 and 96. Shaft 26 is stabilized by thrust bearings 98 and 100. The shafts are provided with appropriate shaft seals 102, 103, 104, 105, 106 and 108.

The housing combustion section is provided with a precombustion chamber 110 associated with each fuel injection means 30 and spark plug means 32. Each chamber 110 opens to the revolving primary combustion chambers 29 through a port 112. Each fuel injection means 30 is provided with an air line 114 leading from a cutoff rotor accumulator air supply annulus 68 to permit a mixture of fuel and air at a relatively low positive pressure to be injected into the respective precombustion chamber 110 for ignition by spark plug means 32 in timed relation to the revolving primary combustion chambers 29. Time means 116 can be conveniently associated with cutoff rotor shaft 56 through bevel gearing to mechanically provide the essential ignition timing.

Blowers 130 may be driven by the cutoff rotor shafts to force air into the housing air intake ports through ducts 132 and the housing air accumulator section. Accumulation of intake air serves to equalize intake air pressure continuously supplied by the blowers and intermittently withdrawn through the intake ports into the annular piston chamber.

The housing central rotary means, planetary piston means and rotary cutoff means have each been provided with a network of water passages designed to permit continuous cooling water or other liquid coolant circulation under pressure. The water intake and outlet for the housing are not shown because they would be adjacent to the distributor manifold from the radiator in the case of the intake and of the water pump, in the case of the outlet, both of which are not shown. Rotary seal means 140, 141 and 142 for supplying water to the rotating members through their respective shafts and rotary seal means 144 and 146 for withdrawing water from the respective shafts are provided. Water passages 148 within the combustion rotor 24 are supplied from means 141 and discharge into the output

shaft 48. Water passages 152 within the cutoff rotors 16 are supplied from means 142 and discharge into shaft 56. The respective shafts are preferably bored radially to provide the water inlet and outlet passages to the combustion and cutoff rotors and the piston disc, and the respective rotors and disc are provided with annuli surrounding the ported shaft sections such that assembly to the shafts is not critically dependent upon water passage alignment.

The central rotary means, planetary piston means, rotary cutoff means, and the housing piston chambers are machined such that these components interfit without contact. The interfit between adjacent surfaces is sufficiently close the pressure seals exist as a result of boundary turbulence. The interfitting annular steps and chambers between adjacent surfaces enhances the boundary turbulence. The various shaft seals insure that pressure differentials will be negligible. During operation of the engine as sequentially depicted in FIGS. 4—11, the piston sections compress air, entrapped between the piston section leading edges and the respective cutoff rotors as the piston sections advance past the housing air intake port, into the primary and secondary combustion chamber sets as each set revolves into adjacency with the cutoff rotor and is sealed therein as the pistons pass through the cutoff rotor piston recesses. During piston confinement by the cutoff rotors, air is entrapped and compressed within the trailing half of each piston recess until the cutoff rotor check valves open and the entrapped air is forced into the cutoff rotor accumulators as the piston recess space is reduced to zero as shown in FIGS. 6—9. Also during piston confinement by the cutoff rotors, fuel injection and ignition commences in the precombustion chambers and advances into the superimposed primary combustion chambers. As the pistons clear the piston recesses, as in FIG. 11 for example, the trailing edges of the respective primary combustion chambers are opened behind the pistons and burning fuel turbulently expands into the piston chamber. Momentarily thereafter the secondary combustion chambers are opened behind the pistons for supply of additional pressurized air for combustion. Early opening of the primary combustion chambers promotes uniformity of compression increased turbulence and a longer more uniform burning period thereby improving engine efficiency. Furthermore, the provision of the larger, secondary combustion chambers as a secondary source of compressed air also promotes more efficient fuel combustion and compression uniformity.

It is believed that the invention will have been clearly understood from the foregoing detailed description of my now preferred illustrated embodiment. Changes in the details of construction may be restored to without departing from the spirit of the invention and it is accordingly my intention that no limitations be implied and that the hereto annexed claims be given the broadest interpretation to which the employed language fairly admits.

I claim:

1. A rotary internal combustion engine of the type comprising a housing; a central combustion rotor rotatably contained in the housing and having a plurality of combustion chambers opening to an annular piston chamber enclosing the peripheral edge of the combustion rotor, and a hollow shaft contained within the housing and axially mounting the combustion rotor at one end; a planetary piston means rotatably contained within the housing and including a piston disc in face-to-face adjacency with one said of the combustion rotor and at least one piston integral with the piston disc and extended parallel to the engine axis in face-to-face adjacency with the peripheral edge of the combustion rotor, and a drive shaft axially extended through the combustion rotor shaft and through at least one end of the housing as a power outlet and axially mounting the piston disc; a cutoff rotor rotatably contained within the housing and positioned to intersect the piston chamber and sweep the peripheral edge of the combustion rotor such that the piston chamber is divided into compression and expansion zones, the cutoff rotor having at least one piston recess for receiving a piston therein to permit

passage of the piston as the piston revolves around the combustion rotor, a cutoff rotor shaft contained within the housing and axially mounting the cutoff rotor; gear train means interconnecting said combustion rotor shaft, drive shaft, and cutoff rotor shaft to rotate the cutoff rotor and the combustion rotor in response to revolution of the piston means such that the piston successively closes off the combustion chambers from the piston chamber as the piston passes through the cutoff rotor piston recess; and fuel injection means adapted to supply the combustion chambers with ignited fuel in timed relation to passage of the piston across the combustion chamber openings.

2. the engine of claim 1 wherein the cutoff rotor is provided with an internal toroidal accumulator chamber in communication with the trailing end portion of the piston recess therein such that air entrapped in such portion during passage of the piston through the piston recess can escape to the accumulator chamber.

3. The engine of claim 1 wherein the combustion rotor is provided with tow sets of combustion chambers consisting of a set of primary relatively shallow combustion chambers provided in the combustion rotor side surface adjacent to the housing and opening to the piston chamber, and a set of secondary relatively deep combustion chambers superimposed with the primary combustion chamber and contained within the combustion rotor and opening to the piston chamber, the trailing edge of each secondary combustion chamber being arranged to lead the trailing edge of the respective superimposed primary combustion chamber such that the primary combustion will be first exposed to the trailing edge of the piston as the piston revolves around the combustion rotor; and wherein the fuel injection means is provided to communicate with the primary combustion chambers.

4. the engine of claim 2 wherein the cutoff rotor accumulator chamber is ported to the hosing and wherein fuel injection means is adapted to receive air from the accumulator chamber through the housing port to prepressurize fuel prior to injection.

5. The engine of claim 1 including rotary-sealed liquid coo-

lant supply means provided on the engine shafts to supply liquid coolant to the shaft interiors; and wherein the engine shafts, combustion rotor, piston means and cutoff rotor are ported to permit liquid coolant to continuously circulate therethrough.

5 6. The engine of claim 5 wherein liquid coolant supply means for the combustion rotor and piston means are provided to introduce liquid coolant into the combustion rotor shaft and piston means shaft independently, and to withdraw liquid coolant from both the combustion rotor and piston means through the piston means shaft.

10 7. A rotary engine of the type comprising a housing having an inlet and an exhaust; a central rotor rotatably contained in the housing and having a plurality of outwardly opening peripheral chambers; an annular piston chamber enclosing the peripheral edge of the central rotor and communicating with said peripheral chambers; and a hollow central rotor shaft contained within the housing and axially mounting the central rotor at one end; a planetary piston means rotatably contained within the housing and including a piston disc in face-to-face adjacency with one side of the central rotor and at least one piston integral with the piston disc and extended parallel to the engine axis in face-to-face adjacency with the peripheral edge of the central rotor, and a drive shaft axially extended 15 through the central rotor shaft and through at least one end of the housing as a power outlet and axially mounting the piston disc; a cutoff rotor rotatably contained within the housing and positioned to intersect the piston chamber and sweep the peripheral edge of the central rotor such that the piston 20 chamber is divided into zones, the cutoff rotor having at least one piston recess for receiving a piston therein to permit passage of the piston as the piston revolves around the central rotor, a cutoff rotor shaft contained within the housing and axially mounting the cutoff rotor; gear train means interconnecting 25 central rotor shaft, drive shaft, and cutoff rotor shaft to rotate the cutoff rotor and the central rotor in response to revolution of the piston means; and means adapted to supply the chambers with propulsion fluid in timed relation to movement of the piston across the peripheral chamber openings.
